UNITED STATES PATENT OFFICE.

JAKOB TOMSICH, OF BRILLIANT, NEW MEXICO.

PICTURE FRAME.

Application filed May 11, 1922. Serial No. 560,078.

To all whom it may concern:

Be it known that I, JAKOB TOMSICH, a citizen of Jugo-Slavia, residing at Brilliant, in the county of Colfax and State of New Mexico, have invented certain new and useful Improvements in Picture Frames, of which the following is a specification.

This invention relates to certain new and useful improvements in picture frames and has particular reference to frames in the form of a flexible strip including spaced openings therein with tabs struck out from the strip adjacent the edges of the openings for supporting a picture within the frame.

15 The invention further embodies in a picture frame of the type above set forth, the provision of frame strips having spaced slots formed in the upper edge thereof and gummed tab extensions carried by the lower edge thereof to be received in an adjacent slot in another picture frame for retaining two or more frames in assembled condition.

20 With the above general objects in view and others that will appear as the nature of 25 the invention is better understood, the same consists of the novel form, combination and arrangement of parts hereinafter more fully described, shown in the accompanying drawing and claimed.

30 In the drawing, wherein like reference characters designate corresponding parts throughout the several views,

Figure 1 is a fragmentary plan view of a picture frame strip constructed in accordance with the present invention showing the picture opening in the strip, the struck-out tabs for supporting the picture adjacent the strip openings and the gummed extension tab and receiving slots at the upper and 40 lower edges thereof,

Figure 2 is a vertical sectional view showing two frame strips connected together with pictures supported thereon, and

45 Figure 3 is a fragmentary plan view of a modified form of picture strip showing the picture vertically disposed upon the strip, eyelets in the upper end of the strip for suspending the same and gummed tabs at the lower edge thereof for cooperation with a 50 strip similar to the form shown in Fig. 1.

Referring more in detail to the accompanying drawing, and particularly to Figs. 1 and 2, there is illustrated a picture frame formed of a relatively long strip 1 of flexible

material such as paper, cardboard or the like 55 having a plurality of spaced elongated rectangular frame openings 2 arranged midway the upper and lower edges thereof, the frame openings 2 being spaced by connecting strip sections 3 and end bars 4.

60 As shown in Figs. 1 and 2, a picture 5 is removably supported upon the strip 1 overlying the frame openings 2, the retaining means therefor embodying tabs 6 struck-out from the frame strip 1 at the opposite ends 65 and lower side of the frame opening, the tabs being bent upon the weakened lines 7 for supporting the picture 5 rearwardly of the strip as shown in Fig. 2.

65 The elongated frame strips 1 are constructed in a manner whereby any number of the strips may be connected together as a unitary device, the upper edges of the strips being provided with spaced slots 8, while the lower edge of the strip carries gummed 70 tab extensions 9 aligned with the slots 8, the tab being inserted in the adjacent slot of another frame strip and bent upon itself to be 75 gummed thereto as shown in Fig. 2.

75 In the form of the invention shown in Fig. 3, the elongated frame strip 1 has vertically disposed elongated rectangular frame openings 2^a formed therein with tabs 6 associated with the frame openings in a manner as disclosed in connection with Fig. 1, the strips 80 illustrated in Fig. 3 being the uppermost frame strip and having eyelets 10 formed in the upper edge thereof for suspending the same. The lower edge of the strip shown in Fig. 3 carries gummed tabs 9 that are associated with the type of strip shown in 85 Fig. 1.

85 From the above detailed description of the device, it is believed that the construction and operation thereof will at once be apparent, it being noted that the pictures 5 are 90 removably supported upon the frame strip 1 by the tabs 6 struck out from the strip while the cooperating tongue and slots 9 and 8 provide for the connecting of strips as 95 illustrated by Fig. 2. If desired, the connecting sections 3 between the frame openings 2 and 2^a may be weakened upon lines to permit folding of the frame strip as in 100 transporting the same.

105 While there are herein shown and described the preferred embodiments of the present invention it is nevertheless to be

understood that minor changes may be made therein without departing from the spirit and scope of the invention as claimed.

What I claim as new is:—

- 5 A picture frame embodying a frame strip having spaced frame openings therein, the upper edge of the strip having spaced slots

therein, and gummed tabs carried by the lower edge of the strip vertically aligned with said slots whereby adjacent strips may be 10 connected together.

In testimony whereof I affix my signature.

JAKOB TOMSICH.
